CONTAINER CUSHIONING MEANS FOR
CONTAINER CARSGraham C. Woodruff, Bronxville, N. Y., assignor
to The L. C. L. Corporation, a corporation of
Delaware

Application January 19, 1934, Serial No. 707,398

21 Claims. (Cl. 105—366)

This invention relates to container cushioning means for container cars of that type in which a fixed side or drop side container car is divided by bulkheads or partitions into sections, bays or compartments to receive interchangeable goods holding containers for the shipment of goods in less than car lots.

Cars of this type, similar to other railway cars, are equipped with regulation draft gears of suitable capacity to absorb all ordinary end shocks occurring in regular operation, but excessive end jars and shocks, caused by switching or sudden brake applications, are often experienced which cannot be fully absorbed by the draft gear and which result in damage to the containers and their contents.

The main object of my invention is to provide cushioning means supplemental to that of the draft gear and operating to effectually cushion the containers against such jars and shocks and to protect the containers and lading against damage therefrom.

A further object of the invention is to provide cushioning means of the character and for the purpose described which will centralize and properly center the containers in their bays or compartments and which may be readily applied to existing cars and used in connection with regulation containers without any necessity for special attention or fastenings or requiring extra time or operations in loading or unloading actions.

With these and other objects in view, which will appear in the course of the subjoined description, the invention consists of the novel features of construction, combination and arrangement of parts hereinafter fully described and claimed, reference being had to the accompanying drawings, in which:

Fig. 1 is a top plan view of a regulation fixed-side or gondola type of container car embodying the invention.

Fig. 2 is a side elevation of the same.

Fig. 3 is a top plan view of a regulation drop-side type of container car embodying the invention.

Fig. 4 is a side elevation of the same.

Fig. 5 is a view on an enlarged scale, partly in plan and partly in horizontal section, of a portion of a container car embodying the invention, showing a container compartment and the cushioning container supporting platform mounted therein.

Fig. 6 is a view in side elevation of the parts shown in Fig. 5.

Fig. 7 is a vertical transverse section on line 7—7 of Fig. 5.

Figs. 8 and 9 are sections taken respectively on lines 8—8 and 9—9 of Fig. 5.

Fig. 10 is a view similar to Fig. 5 of one half of a container compartment on one side of the longitudinal center of the car and showing a modified construction of cushioning means.

Fig. 11 is a view similar to Fig. 6 of the construction shown in Fig. 10.

Fig. 12 is a section on line 12—12 of Fig. 10.

Fig. 13 is a view similar to Figs. 5 and 10 showing another modified construction of cushioning means.

Fig. 14 is a side elevation of the same, partially in section.

Figs. 15, 16 and 17 are vertical transverse sections on lines 15—15, 16—16 and 17—17 of Fig. 13.

Figs. 18 and 19 are vertical longitudinal sections on lines 18—18 and 19—19 of Fig. 13.

Figs. 20 and 21 are views similar to Figs. 13 and 14 showing still another modified construction of cushioning means.

Fig. 22 is a section on line 22—22 of Fig. 20.

Figs. 23 and 24 are views similar to Figs. 20 and 21 showing still another modified construction of cushioning means.

Figs. 25 and 26 are sections on lines 25—25 and 26—26 of Fig. 23.

Figs. 27 and 28 are views similar to Figs. 23 and 24 showing still another modified construction of cushioning means.

Fig. 29 is a section on line 29—29 of Fig. 27.

Referring now more particularly to the drawings, Figs. 1 and 2 show the application of my invention to a container car 1 of gondola type and having fixed sides 2 and fixed ends 3, while Figs. 3 and 4 show the application of my invention to a container car 1a having fixed ends 3a but provided with drop sides 2a, which drop sides may serve simply as hinged drop doors at the sides of container compartments or as combined drop doors and gangways, i. e., loading and unloading platforms over which the containers may travel to and from the car compartments. In both structures the car embodies a car under frame 4 to which are secured transverse bulkheads, abutments or partitions 5 which cooperate with the end walls 3 or 3a and side walls 2 or doors 2a to form a longitudinal series of compartments 6 to receive interchangeable single size containers 7 or double size containers 7', which containers may be either of the type having flat bottoms for supporting them directly

30

35

40

45

50

55

having flat bottoms for supporting them directly

on the bottoms or shelves elevated above the bottoms or of the type having supporting legs to engage sockets in the bottom walls of the compartments to support the containers with 5 their bottoms elevated above the bottoms of the compartments. The bulkheads or abutments, in addition to dividing the car body into container receiving compartments of suitable size, also serve as spacers and stops to hold the containers from undue longitudinal shifting movements on the car. These bulkheads or abutments may be of any suitable construction and terminate at the sides of the car in supporting posts or stanchions 8, to which, as in case 10 of the structure shown in Figs. 1 and 2, the walls 2 and 3 are secured, or which, as in case of the structure shown in Figs. 3 and 4, serve as door jambs for the drop sides or doors 2a, in which case the posts or bulkheads may be divided with 15 suitable fastening members or latches 9 to hold the drop sides or doors in closed position.

In Figs. 5 to 9, inclusive, I have specifically shown one form of my present invention, in which the bottom of each container compartment 6 is formed by a longitudinally movable platform 10 provided at each of its four corners with antifriction bearing wheels or rollers 11 resting and traveling on the upper surfaces of the car side sills 2, and also preferably provided 20 at a central point with half-round or half oval metal strips 13 secured to the underside of the platform throughout its length, resting on the top surface of the center sill cover plate 14, and serving the purpose of supporting the platform 25 and acting as friction brake shoes or snubbers. Lateral movement of the platform is prevented by guiding and retaining strips or brackets 15 and 16 attached to the underside of the platform on each side of the center sill and engageable with the sides thereof to hold the platform from lateral shifting. The platform acts as a movable shock absorbing container support on which the flat bottom of a legless container may directly rest. The platform is provided with sockets 17 to receive the lower ends 30 of the legs of a container having supporting legs.

Each container supporting platform is movable longitudinally in its compartment to an effective degree for shock absorbing actions between the compartment forming bulkheads or 35 abutments and such longitudinal movement of the platform is limited and cushioned by helical cushioning springs 18 bearing against spring seats 19 secured to the end edges of the platform and mounted on suitable spring brackets 20 attached to the underframe cross members 21. The design and capacity of these springs is such that in addition to acting as shock absorbers, to absorb the shocks and jars sustained by the 40 car and causing relative longitudinal shifting movements between the car and container, they will be effective in restoring the platform to and maintaining it normally in a central position, thus providing full movement and capacity for 45 absorption of longitudinal jars or shocks in either direction at all times.

The cushioning action of the springs 18 is or 50 may be supplemented by the shock absorbing actions of spring cushioned container guide members in the form of guide bars or blocks 22 movably mounted in guide seats or guideways 23 on the bulkhead or abutment, the bars or blocks and their guideways preferably extending continuously from side to side of the car. The 55 blocks have beveled and vertical guiding and

bearing surfaces 24 and 25 and serve the function of guide shoes to guide the container into and out of the compartment and to cushion the longitudinal movements of the container as it shifts with the platform. Each guide bar or 5 block is backed by helical cushioning springs 26 disposed in the seats 23 between the blocks and a backing plate 27 forming a part of the bulkhead and each block is provided with stop shoulders 28 engageable with stop flanges or 10 shoulders 29 on the seat 23 to limit the outward movement of the block. The similarly arranged sets of springs 18 and 26 arranged on each bulkhead for coaction with the platforms and 15 containers in adjacent compartments are preferably disposed in alignment so that one and the same bracket or guideway, as the case may be, will serve as a support for springs acting upon the adjacent surfaces of platforms and containers disposed at contiguous sides in two 20 adjoining compartments.

From the foregoing it will be seen that each container is mounted upon a support or platform which is movable longitudinally relatively to the car frame or body to compensate for 25 excessive end shocks or jars due to switching actions or sudden brake applications which cannot be absorbed by the draft gears. These movements of the platforms are cushioned and absorbed by the springs 18 so that damages to 30 the containers, lading and parts of the car due ordinarily to such shocks or jars will be prevented or reduced to the minimum. The cushioning action of the guide blocks or bars which is supplementary to the cushioning action of the 35 platform, provides in conjunction therewith a double means of yieldingly resisting and absorbing end shocks and restoring containers to central position between bulkheads, the cushioning means in each bay or compartment operating 40 entirely independently of the cushioning means in the other bays or compartments whereby each container is separately and independently supported and cushioned against shocks and jars liable to cause damage to the container, its 45 contents or cooperating parts of the car structure. Damage to containers and lading caused by excessive shocks and jars will thus be eliminated or reduced to an appreciable degree.

In Figs. 10, 11 and 12, I have shown a modified form of my invention in which a different construction and arrangement of platform cushioning springs is employed, the modified spring cushioning device providing for the action of opposed springs in either direction in absorbing 55 longitudinal shocks and centering the movable platform. Four pairs of opposed helical springs 30 and coating followers 31 are used in each platform, the springs and followers being supported by cast supports or check plates 32 secured to the car sills and to the car underframe. Suitable brackets 33 secured to the underside of the movable platform engage the spring followers and springs as shown. This construction of spring cushioning means is also applicable to 60 the different arrangements of movable platforms disclosed herein.

In the form of my invention disclosed in Figs. 13 to 18, inclusive, and in Fig. 19, I have shown a modified arrangement of platforms and modifications in the construction of the guiding and cushioning means on the bulkheads. As shown, instead of a transversely continuous one piece 70 platform, a narrow platform 34 supported on rollers resting on the car side sills and auxiliary 75

longitudinal underframe members 34', is provided at each side of a container compartment, which is provided with a fixed bottom or floor 35 between them. The top surface of each movable platform is raised slightly above the surface of the floor 35 so as to allow clearance between the undersides of flat bottom containers and the stationary car floor. Each platform is provided with sockets or recesses 36 to receive the legs or supports on containers so equipped. Longitudinal movement of each platform, which is independent of the platform at the opposite side of the car, is cushioned by helical springs 37 bearing against spring seats 38 attached to each end 5 of the platform and to spring brackets 39 secured to the underframe cross members. Steel strips 40 fastened to the underside of each platform and provided with downwardly projecting portions 41 to lap the top member of the car side sill and auxiliary platform supporting member, serve as friction members to retard or snub longitudinal movement and as lateral retainers for holding the platforms in place. Such additional retaining means as may be found necessary or desirable to assist in holding the movable platform in place on the car under any and all conditions may be employed. This modification also discloses the use of two specifically different forms of bulkhead cushioned container guides, as shown respectively in Figs 18 and 19. In Fig. 18 the construction of the bulkhead, bulkhead guide blocks and means for supporting the blocks is the same as that described with respect to Figs. 5 to 10, inclusive, except that semi-elliptic cushioning springs 42 are employed in place of helical springs. In Fig. 19, however, pressed steel metal guides 43 are used in place of the wooden guide blocks which are formed to the same contour as the wooden guide blocks 40 and function in the same manner. These metal guides are supported and movably held in position by the bulkhead top framing members and by guide bolts 45 secured to the top edge of the bulkhead web plate, as shown. Regularly spaced helical springs 46 are here shown as the cushioning means, but semi-elliptic springs may be employed if desired.

In Figs. 20, 21 and 22, I have shown an arrangement in which the container supporting platform 47 is suspended for movement by means of swing hanger links 48 from the cross bulkheads, said hangers being pivotally attached at their upper and lower ends to brackets 49 on the bulkheads and platform. Longitudinal movement is cushioned by helical springs 50 bearing against brackets 51 secured to the underside of the platform and to the underframe cross members. This platform is suitable for supporting either containers of flat bottom type or containers equipped with legs or other supports.

In Figs. 23 to 26, inclusive, I have shown a platform arrangement similar to that shown in Figs. 20, 21 and 22 in that the platform 52 is supported by swing hangers, except that the hangers 53 are U-shaped and are pivotally attached to brackets 54 attached respectively to the underside of the platform and to the underframe cross members. The cushioning springs 55 here are seated against cast brackets 56 secured to the underframe members and against the brackets 54 on the platform, which are so designed as to serve the double purpose of spring seats and swing hanger bearings.

In Figs. 27, 28 and 29, I have shown an arrangement in which the platform 57, which may

be supported by swing hangers of the type shown in Figs. 20, 21 and 22 or 23 to 26, inclusive, that disclosed in the latter-named case being shown, is spring cushioned in the manner shown in Figs. 10, 11 and 12, the parts used being correspondingly numbered to those shown in the last-named figures. When this swing arrangement and spring cushioning means are conjointly used the brackets attached to the underside of the platform will be required to 10 serve only as bearings for the swing hangers.

From the foregoing description, taken in connection with the drawings, the construction, mode of operation and advantages of my improved supporting and cushioning means for 15 the containers of container cars will be readily understood, without a further and extended description, and it will be seen that a construction is provided which ensures protection to the cars, containers and lading from end shock or jars 20 which has not been obtainable by constructions heretofore in use and whereby damage due to these causes are overcome or reduced to a substantial degree. While the structures disclosed are preferred, it is to be understood that they 25 are merely exemplificative, as many changes in the form, construction and arrangement of parts may be made within the scope of the appended claims without departing from the spirit or sacrificing any of the advantages of the invention. 30

It will be understood that any of the various cushioned bulkheads illustrated in Figs. 5 to 19, inclusive, can be used in conjunction with any of the platform arrangements shown in Figs. 20 35 to 29, inclusive, and that, in general, the supporting and cushioning features disclosed are interchangeable and that accordingly any combination of platform and cushioned bulkheads 40 may be used.

It will also be understood that the cushioning devices embodying the invention, while readily applicable to container cars of the drop-side type, they are, as shown, also readily applicable to cars of the rigid side type when divided 45 into compartments by the use of cross bulkheads or partitions of the kind disclosed or any equivalent thereof.

While the cushioning and centering devices for the movable platforms and for various 50 styles of cushioning bulkhead guide blocks consist of helical springs, or, in case of the cushioned bulkheads, either helical or semi-elliptical springs suitably positioned between the platform or cushioned guide blocks, any suitable shock 55 absorbing or cushioning device or media may be employed to secure the desired cushioning actions.

It may be remarked that a possible adaptation of the invention to a rigid side car falling 60 clearly within the scope of the invention would consist of a skeleton framework designed to fit within the fixed car sides and ends in the form of a floating cradle provided with cushioning springs of suitable number and capacity to absorb longitudinal shocks and jars, providing supplementary means in addition to the regular draft gears for protecting the containers and lading from damage due to impact or rough handling. With this arrangement it would, of 70 course, be impracticable to protect each container individually, though practical to protect all or a number of the containers in groups, the complete battery of containers or group or groups of them, as the case may be, being sup- 75

ported in a movable framework which may be provided with the usual guide shoes or fixed transverse bulkheads or other suitable means to prevent contact of the containers with each other.

5. What I claim is:—

1. In a container car, a car frame, a car body mounted thereon, transverse abutments on the body forming a longitudinal series of container compartments, a container supporting platform mounted in each compartment for movement longitudinally of the car, abutments on the frame, cushioning springs on the frame engaging the abutments on the frame and extending 10 on each side of an abutment on the body for opposing longitudinal movements of container platforms in adjacent compartments, and cushioned container guides on the abutments on the body at an elevation above said cushioning springs.

2. In a container car, a car frame, a car body mounted thereon, transverse abutments on the body forming a longitudinal series of container compartments, a container supporting platform 20 mounted in each compartment for movement longitudinally of the car, guides on the frame for guiding the platforms in a longitudinal direction and preventing transverse movement thereof, abutments on the frame, cushioning 25 springs on the frame between said abutments on the frame and the container platforms in adjacent compartments for opposing longitudinal movements of container platforms in adjacent compartments, and cushioned container guides 30 on the abutments at an elevation above said cushioning springs.

3. In a container car, the combination of a car frame, a car body, a container supporting platform mounted on the frame for movement 40 longitudinally of the car, transverse abutments on the frame at each end of the platform, spring means limiting and cushioning the longitudinal movements of the platform, friction shoes on each platform and in sliding frictional engagement with the frame to oppose longitudinal movement of the platform, container guides 45 movably mounted on the abutments, and spring means backing and cushioning the movements of said guides.

4. In a container car, a car frame, a car body, transverse abutments on the body, guiding means on the frame, a container supporting platform movable longitudinally of the frame on said guiding means and held from lateral 50 movement thereby, cushioning springs between the platform and car frame for cushioning longitudinal movements of said platform, container guide members movably mounted on the abutments, and cushioning means on the abutments 55 yieldingly backing the guide members to cushion longitudinal movements of the container on the platform.

5. In a container car, a car frame, a car body, transverse abutments on the frame forming 60 container compartments, a container supporting platform movable longitudinally of the frame in each compartment, cushioning springs opposing longitudinal movement of the platform in each direction, transversely extending container guide bars movably mounted on the abutments extending across the compartments, and container cushioning means on the abutments 65 backing said guides.

6. In a container car, a car frame, a car body transverse abutments on the body forming 70

7. container compartments, a container supporting platform movable longitudinally of the frame in each compartment, cushioning springs disposed on the frame between the frame and platform and bearing on the ends of the platform 5 for opposing longitudinal movement of the platform in each direction, container guides movably mounted on the abutments, and cushioning means backing said guides.

8. In a container car, the combination of a car frame, a car body, stationary transverse bulkheads in the car body dividing the same into a plurality of container receiving compartments, a container supporting platform mounted in each compartment for movement longitudinally 10 of the car, means interposed between each platform and the underframe for normally maintaining the platform in a neutral position and opposing and cushioning longitudinal movements thereof, and means on the abutments at 20 each side of each container compartment for normally maintaining a container on the platform thereof in a neutral position with respect to the platform and yieldingly opposing movements of said container longitudinally of the 25 car, said means presenting guiding surfaces to additionally serve the function of guiding a container with relation to the platform when elevated into or deposited in its receiving compartment.

9. In a container car, the combination of an underframe, a car body, stationary transverse bulkheads disposed in the car body and separating the same into a plurality of container receiving compartments, said bulkheads being 30 provided with pockets, a longitudinally movable container supporting platform mounted in each compartment, means interposed between said platform and the underframe for normally maintaining the platform in a neutral position 40 in its compartment and yieldingly opposing longitudinal movements thereof, guiding members movably mounted in the pockets of the abutments for guiding a container when inserted downwardly within or lifted for deposit upon or 45 removal from the platform, and cushioning means in the pockets of the abutments for action thereon to yieldingly oppose movements of said guiding members, whereby said guiding means are adapted to act as cushion buffers to 50 yieldingly oppose longitudinal movement of the container on its platform and to adapt the container to shift longitudinally with the platform.

10. In a container car, the combination of a car underframe having members presenting 55 track surfaces and a friction surface, a car body mounted on the underframe, stationary transverse abutments within the car body and dividing the same into a plurality of container receiving compartments, a longitudinally movable container supporting platform in each compartment having roller bearing contact with the track surfaces of the underframe, cushioning means interposed between each platform and the car underframe to yieldingly oppose 60 longitudinal movements of the platform in either direction, and friction shoes upon the platform engaging the friction surface of the underframe to frictionally retard the platform in its longitudinal movements.

11. In a container car, the combination of a car underframe having members presenting track surfaces and a friction surface, a car body mounted on the underframe, stationary transverse abutments within the car body and di- 75

viding the same into a plurality of container receiving compartments, a longitudinally movable container supporting platform in each compartment having roller bearing contact with the track surfaces of the underframe, cushioning means interposed between each platform and the car underframe to yieldingly oppose longitudinal movements of the platform in either direction, spring cushioned guides on the abutments for guiding a container into and out of its compartment and yieldingly opposing longitudinal movements in either direction of the container on its platform, and friction shoes upon the platform engaging the friction surface of the underframe to frictionally retard the platform in its longitudinal movements.

11. In a container car, the combination of a car underframe having side sills and a center sill, a car body, stationary transverse bulkheads within the car body and dividing the same into a plurality of container receiving compartments, a longitudinally movable container supporting platform in each compartment having roller bearing engagement with the side sills of the underframe, cushioning means interposed between each platform and the underframe for yieldingly opposing longitudinal movements of the platform in either direction, and friction shoes on each platform engaging the center sill of the car underframe and coacting therewith to frictionally retard the longitudinal movements of the platform.

12. In a container car, the combination of a car underframe, a car body, stationary transverse abutments arranged within the car body and dividing the same into a plurality of container receiving compartments, a longitudinally movable container supporting platform in each compartment, means interposed between the underframe and each platform for normally maintaining the platform in a neutral position in its compartment and yieldingly opposing longitudinal movements of the container in either direction, and cushioning means upon the sides of the bulkheads within each compartment acting on a container support on the platform to yieldingly oppose independent longitudinal movement in either direction on the platform while permitting said container to shift longitudinally with the platform.

13. In a container car, the combination of a car underframe, a car body, stationary transverse bulkheads within the car body and dividing the same into a plurality of container receiving compartments, each bulkhead being provided with pockets facing the adjoining compartments and having a partition supporting said pockets, a longitudinally movable container supporting platform within each compartment, cushioning means for opposing longitudinal movements of said platform in opposite directions, guiding members movably mounted in the pockets of the abutments and acting to guide a container onto and off of a platform when deposited within and withdrawn from a compartment, and cushioning springs disposed in the pockets of the abutments between the separating partitions and the guiding members and backing said guiding members to yieldingly oppose independent longitudinal shifting movements of a container on its platform.

14. In a container car, the combination of a car underframe, a car body, transverse bulkheads within the car body dividing the same into a plurality of container receiving compartments,

a stationary floor within each compartment, longitudinally movable container supporting platforms in each compartment on opposite sides of the stationary floor, means connecting said platforms in guided relation to the car underframe, means interposed between the car underframe and the respective platforms in each compartment for yieldingly opposing longitudinal shifting movements of said platforms, container guide members upon the transverse abutments, and cushioning means on the abutments backing said guide members.

15. In a container car, the combination of a car underframe, a car body, stationary transverse bulkheads within the car body dividing the same into a plurality of container receiving compartments, a longitudinally movable container supporting platform in each compartment, links pivotally connecting each platform with one of the aforesaid stationary parts of the car structure for swingingly supporting the platform for longitudinal movements, and cushioning means yieldingly controlling the longitudinal shifting movements of each platform.

16. In a container car, the combination of a car underframe, a car body, stationary transverse bulkheads within the car body, and dividing the same into a plurality of container receiving compartments, a longitudinally movable container supporting platform in each compartment, links pivotally suspending the platforms from the bulkheads, and cushioning means for opposing the longitudinal movements of the platforms.

17. In a container car, the combination of a car underframe, a gondola type car body mounted thereon, transverse bulkheads dividing the body into a plurality of container receiving compartments, a longitudinally movable container supporting platform at the bottom of each compartment, abutments on the underframe, and cushioning means on the underframe beneath each bulkhead engaging said abutments on the underframe and extending into adjacent compartments on opposite sides of said bulkhead and engaging adjacent ends of the platforms in said compartments to cushion the longitudinal movements of said platforms.

18. In a container car, the combination of a car underframe, a gondola type car body mounted thereon, transverse bulkheads dividing the body into a plurality of container receiving compartments, a longitudinally movable container supporting platform at the bottom of each compartment, abutments on the underframe, cushioning means on the underframe beneath each bulkhead engaging said abutments on the underframe and extending into adjacent compartments on opposite sides of said bulkhead and engaging adjacent ends of the platforms in said compartments to cushion the longitudinal movements of said platforms, and container guiding and cushioning elements on the bulkhead above the level of the platforms.

19. In a container car, the combination of a car underframe, a gondola type car body mounted thereon, transverse bulkheads dividing the body into a plurality of container receiving compartments, a longitudinally movable container supporting platform at the bottom of each compartment, abutments on the underframe, cushioning means on the underframe beneath each bulkhead engaging said abutments on the underframe and extending into adjacent compartments on opposite sides of said bulkhead and

engaging adjacent ends of the platforms in said compartments to cushion the longitudinal movements of said platforms, guide sockets at the top of each bulkhead on opposite sides thereof, 5 backing members separating the sockets at opposite sides of each bulkhead, container guiding members movably mounted in said sockets, and cushioning springs disposed in the sockets between the container guiding and backing 10 members.

20. In a container car, a car underframe having side sills, a center sill and cross beams connecting said sills, a car body carried by said underframe, transverse bulkheads dividing said 15 body into a plurality of container receiving compartments, a longitudinally movable container supporting platform disposed in each compartment above said sills and having followers depending therefrom, check plates car-

ried by adjacent cross beams of the underframe, and cushioning springs between said followers and check plates.

21. In a container car, a car underframe having side sills and a center sill, a car body carried by said underframe, transverse bulkheads dividing said body into a plurality of container receiving compartments, a longitudinally movable container supporting platform in each compartment, each having roller bearing engagement with the side sills, abutments on the underframe beneath adjacent compartments, cushioning means engaging the abutments on the underframe and also engaging the platforms in adjacent compartments to cushion the movements of said platforms, and friction shoes on each platform engaging the center sill to frictionally check the movements of the platform. 10 15

GRAHAM C. WOODRUFF.
